(57) **CLAIM**

We claim the ornamental design for a vehicle rack component for supporting a bicycle, as shown and described.

DESCRIPTION

FIG. 1 is a top, rear, and right-side perspective view of a vehicle rack component for supporting a bicycle constructed in accordance with the present invention;

FIG. 2 is a right-side elevation view thereof;

FIG. 3 is a left-side elevation view thereof;

FIG. 4 is a top plan view thereof;

FIG. 5 is a bottom plan view thereof;

FIG. 6 is a front elevation view thereof; and,

FIG. 7 is a rear elevation view thereof.

The broken lines in the drawings illustrate portions of the vehicle rack component for supporting a bicycle that form no part of the claimed design.
